(57) **CLAIM**

The ornamental design for a promotional assembly, as shown and described.

DESCRIPTION

FIG. 1 is a perspective view of a promotional assembly in accordance with the present invention wherein the promotional assembly includes an advertising portion and a coupon card portion;

FIG. 2 is a front view of the promotional assembly;

FIG. 3 is a rear view of the promotional assembly showing a number of coupons in phantom;

FIG. 4 is a right side elevational view of the promotional assembly;
FIG. 5 is a left side elevational view of the promotional assembly;
FIG. 6 is a bottom side elevational view of the promotional assembly; and,
FIG. 7 is a top side elevational view of the promotional assembly.

The three broken line segments in FIGS. 1–3 represent perforations, which form part of the claimed design. The elements shown in phantom are for illustrative purposes only and form no part of the claimed design.
